SPECIFICATION forming part of Design No. 32,468, dated April 10, 1900.

Application filed January 8, 1900. Serial No. 786. Term of patent 7 years.

To all whom it may concern:

Be it known that I, CHARLES J. AHREN-FELDT, a citizen of the United States, residing at the city of New York, county of New York, and State of New York, have invented and produced a new and original Design for a Plate or Similar Article, of which the following is a specification, reference being had to the accompanying drawing, forming a part thereof.

In the said drawing the figure is a plan view of a plate with my design placed thereon.

A consists of two spiral ornaments A² A³ and a semicircular ornament A', all of the same character, proceeding from a common stem A⁴ at either side of an upright stalk A⁵ bearing leaves and flowers. The spiral and curved ornaments are supplemented by small stems bearing leaves and flowers a and fruit-bearing tendrils a' and a².

B consists of a pair of abutting spiral leaf-like ornaments B', with an upright stem B² bearing leaves and flowers interposed between, and a leaf-like ornament B³ at the outer terminal of each spiral. B' and B³ are supplemented by small stems bearing flowers b and fruit-bearing tendrils b' b² similar to a, a', and a², respectively.

C consists of a pair of semicircular ornaments C', each supplemented by stems bearing leaves and flowers C² C³, the two ornaments forming a circular panel.

A and B are alternated to form a circular border, while C is located at the center thereof.

This design may be applied to articles other than plates.

What I claim is—

The design for a plate or similar article substantially as herein shown and described.

Signed at New York city, New York, this 28th day of December, 1899.

CHARLES J. AHRENFELDT.
